CLAIM

The ornamental design for the oval swing door medicine cabinet, as shown and described.

DESCRIPTION

FIG. 1 illustrates a perspective view of oval swing door medicine cabinet;

FIG. 2 illustrates a front elevational view thereof;

FIG. 3 illustrates a side view thereof;

FIG. 4 illustrates a top plane view thereof; and,

FIG. 5 illustrates cross section view taken at line 5—5 of FIG. 2.

The broken lines shown in the drawings are for illustrative purposes only and form no part of the claimed design.
